UNITED STATES PATENT OFFICE.

ALBERT CANDY MOORE, OF BELLOWS FALLS, VERMONT.

PAPER-HOLDER.

SPECIFICATION forming part of Letters Patent No. 297,618, dated April 29, 1884.

Application filed December 26, 1883. (No model.)

To all whom it may concern:

Be it known that I, ALBERT CANDY MOORE, of Bellows Falls, in the county of Windham, of the State of Vermont, have invented a new and useful Improvement in Water-Closet-Paper Holders; and I do hereby declare the same to be described in the following specification and represented in the accompanying drawings, of which—

10 Figure 1 is a perspective view, Fig. 2 a transverse section, and Fig. 3 a longitudinal section, of a paper-holder containing my invention, the nature of which is defined in the claims hereinafter presented.

15 The holder is to support a roll of paper and to enable portions thereof to be separated from the remainder in manner and by means as described and as occasion may require.

The holder is represented as adapted to such 20 a roll, which in the drawings is shown at A as wound upon a tube or cylinder, *a*, of wood, into the ends of which the journals *b b* of the legs *c c* of the bail *B* are inserted. This bail, formed of wire, bent as shown, has pivoted to 25 it, at its middle, a screw, *C*, or some other proper device for fastening it to a wall.

A combined knife, *e*, and brake *f*, formed 30 of sheet metal, bent as represented, is shown at *D* as secured to the bail by arms *d d*, extending from them and pivoted to it, so as to enable the brake to rest against the periphery 35 of the roll of paper. The brake makes an angle of about ninety degrees with the knife, whose cutting-edge is its outer edge, the blade of the knife being by preference bent upward, as shown, just in rear of the said cutting-edge. This brake with the arms may be in 40 one piece of wire, or it may be the back of the knife; but it is preferable to have it formed and arranged with the knife in manner as represented. There extends between the arms, and directly over and parallel with the brake 45 and knife, a rung or guide, *g*, between which and the brake and over the knife the paper from the roll is to extend in manner as represented at *h*. Having drawn forward the

paper sufficiently from the guide, the paper is to be borne down upon the cutting-edge of the knife so as to depress the knife and crowd the brake against the roll, whereby the said roll will be stopped from revolving while the paper may be severed or cut by the knife. The part of the paper that may lap on the knife will remain intact, ready for being seized, for the purpose of drawing forward over the knife more of the paper of the roll, such roll, while paper is being so drawn from it, turning freely on the journals of the bail.

I do not claim a paper-holder constructed and to operate as represented in the United States Patent No. 193,175, my paper-holder having one or more appliances not incident thereto. Nor do I claim paper-holders made as represented in the United States Patents Nos. 248,323 and 285,398, for in neither of such 65 patents is a brake shown as fixed to the knife or cutter, and by it caused to bear against the roll of paper while a part of such roll is being severed from the rest by the knife.

I claim—

1. The knife connected to the bail and provided with a brake to extend from it, the said knife, against the roll of paper, and to be borne against it by the draft of the strip of paper on the knife while the latter may be in 75 the act of separating the paper, all being substantially as set forth.

2. The bail provided with the guide and knife, arranged as set forth, and with a brake to extend from the knife against the roll of 80 paper, all being substantially and to operate as represented.

3. The combination of the bail provided with the supporting screw or device, with the knife and brake arranged and connected with 85 each other as described, and connected with the bail by arms applied thereto, as set forth.

ALBERT CANDY MOORE.
